GUN WITH RECOILING BARREL.

1,020,233.

Specification of Letters Patent. Patented Mar. 12, 1912.

Application filed November 14, 1910. Serial No. 592,303.

To all whom it may concern:

Be it known that I, KARL VÖLLER, engineer, a subject of the German Emperor, residing at 17 Jülicherstrasse, Dusseldorf, Germany, have invented certain new and useful Improvements in Guns with Recoiling Barrels; and I do hereby declare the following to be a full, clear, and exact description of the invention, such as will enable others skilled in the art to which it appertains to make and use the same.

In guns having a recoiling barrel which is returned by a spring, it is apt to happen that the energy imparted to the barrel by the spring is not completely absorbed by the brake at the end of the return movement so that the barrel strikes forcibly the projection which determines the forward position of the barrel. In order to minimize this shock elastic material, such as rubber buffers, has been provided on the projections.

The present invention consists in eliminating such elastic material and using the return spring for producing the effect thereof.

The construction according to the invention is shown in the accompanying drawings wherein—

Figure 1 shows the return mechanism in longitudinal section and Fig. 2 partly in section and partly in rear elevation.

The barrel *a* is guided in the tubular cradle *b* and slides therein during the recoil, the energy of the recoil being absorbed by a brake, not shown in the drawings, and the return spring hereinafter described being compressed. In the case shown two exactly similar return mechanisms are used, one on each side of the middle vertical plane of the gun barrel. Two rods *d* are fixed by means of bayonet joints *e* to a depending lug *c* on the cradle *b*, and extend rearwardly. Against a collar *f* on the rod abuts a disk *g* which can slide on the rod, but which is prevented from rotating by a tongue and groove. This disk *g* serves as a support for the return spring *h*, the other end of which abuts against a second disk *i*. Axial movement of the disk *i* in that direction in which the return spring expands is prevented by the shoulder *k* of an elongated screw nut *l*; in the other direction the disk can move against the pressure of the return spring. The nut *l* is screwed on to the threaded re-

duced end of the rod *d*, and is of greater part of the same external diameter as the rod *d*. It serves for adjusting the preliminary compression of the return spring. The latter is surrounded by a cylinder *m*, the partly closed end *n* of which abuts against the disk *g*. The other end of the cylinder *m* is closed by a cover *o* fixed to it by a bayonet joint and secured by a pin *p*. The cover is so formed that it lies closely against the disk *i* which is prevented from rotating in the cylinder *m* by a tongue and groove, but has a certain amount of play relatively to the rod *d* or nut *l*.

The cylinder *m* is accommodated in a bore in the cradle *b* and has two alined lugs *q* on one side which engage between them a depending lug *r* on the barrel *a*. The rearward lug *q* has a spring pin *s* by means of which the cylinder *m* is locked to the barrel in the following manner:—The cylinder is inserted in its bore in such a position that the lugs *q* can slide past the lug *r*; when the lug *r* registers with the space between the lugs *q* the cylinder *m* is rotated on its axis until the lugs *q* engage the lug *r*, whereupon the spring pin *s* locks the cylinder *m*, preventing it from being again turned. The position of the lugs *q* relatively to the engaging parts of the bayonet joint *e* on the rod *d* is such that by the rotation of the cylinder *m*, which is shared by the rod *d*, the lugs *q* engage with lug *r* at the same time that the parts of the bayonet joint *e* engage with each other. By this arrangement it is possible to remove the whole return mechanism from the cradle while the spring is in place.

The mechanism operates as follows: When the barrel *a* recoils its lug *r* carries with it the cylinder *m*, while the rod *d* remains at rest. The end *n* of the cylinder brings the disk *g* backward, while the second disk *i* is held stationary by the nut *l* and rod *d*. The spring *h* is therefore compressed during the recoil. At the end of the recoil the spring *h* expands and moves the barrel *a* forward, since it presses the disk *g*, end *n* of cylinder *m* and therefore the lug *r* of the barrel *a*. If during the return the barrel *a*, after arriving at the position shown, continues to move forward, because the brake has not absorbed the whole of the energy, the spring *h* cannot expand further, for the disk *i* is held by the collar *l*.

f. But the end *o* of the cylinder *m* can carry the disk *i* with it and can thus compress the spring *h*, which therefore itself absorbs the rest of the energy and serves as a buffer for the forward movement.

Having thus described the nature of my invention and the best means I know of carrying the same into practical effect, I claim:

- 10 1. In a gun having a recoiling barrel and a return spring, a cradle, a rearwardly extending rod fixed to the cradle and surrounded by the spring, two disks adapted to slide on the said rod and to hold the said spring in compression between them and stops on the said rod adapted to prevent the spring in its normal state of compression from moving the disks farther apart from each other.
- 15 2. In a gun having a recoiling barrel and a return spring, a cradle, a rearwardly extending rod fixed to the said cradle and surrounded by the spring, two disks adapted to slide on the said rod and to hold the said spring in compression between them, a cylinder adapted to move with the barrel and

surrounding the said spring, means for preventing one of the said disks from sharing any movement of the cylinder except a forward movement beyond the normal position and means for causing the other disk to share all movements of the cylinder except a forward movement beyond the normal position.

3. In a gun having a recoiling barrel and a return spring a cradle, a rearwardly extending rod surrounded by the spring, a bayonet joint connecting the said rod with the said cradle, a cylinder surrounding the said spring and a bayonet joint connecting the said cylinder with the barrel, the relative position of the engaging parts of the two bayonet joints being such that both joints are put into engagement by the same rotation of the cylinder on its axis.

In testimony whereof, I have signed this specification in the presence of two subscribing witnesses.

KARL VÖLLER.
